(57) **CLAIM**

The ornamental design for a dehumidifier, as shown and described.

DESCRIPTION

FIG. 1 is a perspective view of a dehumidifier, showing our new design;
 FIG. 2 is a front view thereof;
 FIG. 3 is a rear view thereof;
 FIG. 4 is a side view thereof;
 FIG. 5 is another side view thereof;
 FIG. 6 is a top view thereof;
 FIG. 7 is a bottom view thereof; and,
 FIG. 8 is an enlarged view of portion 8, as shown in FIG. 6. The broken lines illustrating portions of the dehumidifier are environmental purposes only and form no part of the claimed design.
 The dot-dash broken lines encircling enlargement portions of the design form no part of the claimed design.
